(57) **ABSTRACT**

A light-emitting device includes: a first light-emitting unit that extends in one direction and that has a first emission surface that emits light located along the one direction; a second light-emitting unit that is located in the one direction with respect to the first light-emitting unit, that extends in the one direction, and that has a second emission surface that emits light located along the one direction; a cleaning unit that is capable of moving in the one direction and an opposite direction that is opposite to the one direction to clean the first emission surface; a transmission part that extends from the cleaning unit in the one direction and that transmits a moving force for moving the cleaning unit to the cleaning unit; and an extending part that extends from the transmission part in the one direction to elongate the transmission part. When the cleaning unit is positioned furthest in the opposite direction, an end of the extending part in the one direction is located further in the one direction than a midpoint between an end of the first light-emitting unit in the one direction and an end of the second light-emitting unit in the one direction.

LIGHT-EMITTING DEVICE

CROSS-REFERENCE TO RELATED APPLICATIONS

This is a continuation of International Application No. PCT/JP2020/028124 filed on Jul. 20, 2020, and claims priority from Japanese Patent Application No. 2020-054931 filed on Mar. 25, 2020.

BACKGROUND

(i) Technical Field

The present disclosure relates to a light-emitting device.

(ii) Related Art

Japanese Unexamined Patent Application Publication No. 2007-130789 describes a structure including a support member that moves in a longitudinal direction of a light-emitting diode (LED) print head so that a blade member cleans a light-emitting surface. The support member moves while contact parts thereof are in contact with a photoconductor drum.

SUMMARY

An example of a light-emitting device may have a structure including a light-emitting unit, a cleaning unit, and a transmission part. The light-emitting unit extends in one direction and has an emission surface along the one direction. The cleaning unit moves in the one direction to clean the emission surface. The transmission part extends in the one direction from the cleaning unit and transmits a moving force for moving the cleaning unit to the cleaning unit. This structure will be hereinafter referred to as "structure A".

In structure A, the light-emitting unit may have another light-emitting unit located further in the one direction with respect thereto. In such a case, when the transmission part is accessed from a region in the one direction with respect to the other light-emitting unit, the distance to the transmission part is increased, and the transmission part cannot be easily accessed from the region in the one direction.

Aspects of non-limiting embodiments of the present disclosure relate to a structure that allows easier access to the transmission part from the region in the one direction compared to a structure in which the moving force is transmitted to the cleaning unit only through the transmission part.

Aspects of certain non-limiting embodiments of the present disclosure overcome the above disadvantages and/or other disadvantages not described above. However, aspects of the non-limiting embodiments are not required to overcome the disadvantages described above, and aspects of the non-limiting embodiments of the present disclosure may not overcome any of the disadvantages described above.

According to an aspect of the present disclosure, there is provided a light-emitting device including: a first light-emitting unit that extends in one direction and that has a first emission surface that emits light located along the one direction; a second light-emitting unit that is located in the one direction with respect to the first light-emitting unit, that extends in the one direction, and that has a second emission surface that emits light located along the one direction; a cleaning unit that is capable of moving in the one direction and an opposite direction that is opposite to the one direction

2

to clean the first emission surface; a transmission part that extends from the cleaning unit in the one direction and that transmits a moving force for moving the cleaning unit to the cleaning unit; and an extending part that extends from the transmission part in the one direction to elongate the transmission part, wherein when the cleaning unit is positioned furthest in the opposite direction, an end of the extending part in the one direction is located further in the one direction than a midpoint between an end of the first light-emitting unit in the one direction and an end of the second light-emitting unit in the one direction.

BRIEF DESCRIPTION OF THE DRAWINGS

Exemplary embodiments of the present disclosure will be described in detail based on the following figures, wherein:

FIG. 1 is a schematic diagram illustrating an image forming apparatus including exposure devices according to a first exemplary embodiment;

FIG. 2 is a perspective view of an exposure device according to the first exemplary embodiment;

FIG. 3 is a plan view of the exposure device according to the first exemplary embodiment;

FIG. 4 is a cross-sectional view of the exposure device according to the first exemplary embodiment (sectional view taken along line IV-IV in FIG. 2);

FIG. 5 is a perspective view of a light-emitting unit included in the exposure device according to the first exemplary embodiment;

FIG. 6 is a perspective view of a cleaning unit included in the exposure device according to the first exemplary embodiment;

FIG. 7 is a cross-sectional view of cleaning units included in the exposure device according to the first exemplary embodiment;

FIG. 8 is a perspective view of a support part included in the exposure device according to the first exemplary embodiment;

FIG. 9 is a perspective view of another support part included in the exposure device according to the first exemplary embodiment;

FIG. 10 is a plan view of an exposure device according to a modification; and

FIG. 11 illustrates the structure of a rendering apparatus including a light-emitting device according to a second exemplary embodiment.

DETAILED DESCRIPTION

Exemplary embodiments of the present disclosure will be described with reference to the drawings.

First Exemplary Embodiment

55 Image Forming Apparatus 10

The structure of an image forming apparatus 10 including exposure devices 40 according to a first exemplary embodiment will now be described. FIG. 1 is a schematic diagram illustrating the structure of the image forming apparatus 10 according to the present exemplary embodiment. In the following description, a +X direction, a -X direction, a +Y direction, a -Y direction, a +Z direction, and a -Z direction are defined as directions shown by the arrows in the drawings. In the following description, an "X direction" without + or - may mean "both +X and -X directions" or "either one of +X and -X directions"; a "Y direction" without + or - may mean "both +Y and -Y directions" or "either one of +Y

and -Y directions"; and a "Z direction" without + or - may mean "both +Z and -Z directions" or "either one of +Z and -Z directions". The X direction, the Y direction, and the Z direction cross each other (more specifically, are orthogonal to each other).

In the drawings, a circle with an X in the middle represents an arrow going into the page, and a circle with a dot in the middle represents an arrow coming out of the page. Dimensional ratios between portions of components illustrated in the drawings in the X, Y, and Z directions and dimensional ratios between the components in the X, Y, and Z dimensions may differ from the actual ratios.

The image forming apparatus 10 illustrated in FIG. 1 is an example of an image forming apparatus that forms an image on a recording medium. More specifically, the image forming apparatus 10 is an electrophotographic image forming apparatus that forms a toner image (example of an image) on a recording medium P. The toner is an example of powder.

Still more specifically, the image forming apparatus 10 may form a multiple-color image. The image forming apparatus 10 may be a full-color printer for commercial printing required to form a particularly high-quality image. The image forming apparatus 10 is a wide image forming apparatus capable of forming an image on a recording medium P having a large medium width (that is, dimension in the Z direction). More specifically, the image forming apparatus 10 is capable of forming an image on a recording medium P having a width greater than a medium width of a longitudinally fed B3-size sheet (that is, greater than 364 mm). Still more specifically, for example, the image forming apparatus 10 is capable of forming an image on a recording medium P having a width greater than or equal to a medium width of a longitudinally fed A2-size sheet (that is, 420 mm) and less than or equal to a medium width of a transversely fed BO-size sheet (that is, 1456 mm). In the present exemplary embodiment, the image forming apparatus 10 is capable of forming an image on a recording medium P having a width equal to a medium width of, for example, a transversely fed B2-size sheet (that is, 728 mm).

The image forming apparatus 10 includes an image forming unit 14 and a fixing device 16. The components (the image forming unit 14 and the fixing device 16) of the image forming apparatus 10 will now be described.

Image Forming Unit 14

The image forming unit 14 has a function of forming toner images on a recording medium P. More specifically, the image forming unit 14 includes toner-image forming units (22Y, 22M, 22C, and 22K) and a transfer device 17.

Toner-Image Forming Units 22 (22Y, 22M, 22C, and 22K)

The toner-image forming units 22 illustrated in FIG. 1 are provided to form toner images of respective colors. In the present exemplary embodiment, four toner-image forming units 22 of respective colors, which are yellow (Y), magenta (M), cyan (C), and black (K), are provided. In FIG. 1, the letters Y, M, C, and K represent the respective colors.

The toner-image forming units 22 of the respective colors have similar structures except for the toners used therein. Therefore, in FIG. 1, only components of the toner-image forming unit 22K, which serves as a representative example of the toner-image forming units 22 of the respective colors, are denoted by reference numerals.

Each of the toner-image forming units 22 of the respective colors includes a photoconductor drum 32 that rotates in one direction (for example, counterclockwise in FIG. 1). Each of the toner-image forming units 22 of the respective colors also includes a charging device 23, an exposure device 40, and a developing device 38.

In each of the toner-image forming units 22 of the respective colors, the charging device 23 charges the photoconductor drum 32. The photoconductor drum 32 charged by the charging device 23 is exposed to light by the exposure device 40, so that an electrostatic latent image is formed on the photoconductor drum 32. The electrostatic latent image formed on the photoconductor drum 32 by the exposure device 40 is developed by the developing device 38, so that a toner image is formed. The structure of the exposure device 40 will be described in detail below.

Transfer Device 17

The transfer device 17 illustrated in FIG. 1 transfers the toner images formed by the toner-image forming units 22 to the recording medium P. More specifically, the transfer device 17 performs a first transfer process in which the toner images on the photoconductor drums 32 of the respective colors are transferred to a transfer belt 24, which serves as an intermediate transfer body, in a superposed manner. Then, the transfer device 17 performs a second transfer process in which the superposed toner images are transferred to the recording medium P. As illustrated in FIG. 1, the transfer device 17 includes a transfer belt 24, first transfer rollers 26, and a second transfer roller 28.

The first transfer rollers 26 transfer the toner images on the photoconductor drums 32 of the respective colors to the transfer belt 24 at first transfer positions T1 between the photoconductor drums 32 and the first transfer rollers 26. In the present exemplary embodiment, a first transfer electric field is applied between each of the first transfer rollers 26 and the corresponding one of the photoconductor drums 32, so that the toner images formed on the photoconductor drums 32 are transferred to the transfer belt 24 at the first transfer positions T1.

The toner images are transferred from the photoconductor drums 32 of the respective colors to an outer peripheral surface of the transfer belt 24. As illustrated in FIG. 1, the transfer belt 24 is loop-shaped and is positioned by being wrapped around plural rollers 39. A driving roller 39D, which is one of the rollers 39, may be rotated by a drive unit (not shown) to rotate the transfer belt 24 in the direction of arrow A. Referring to FIG. 1, the rollers 39 also include an opposing roller 39B that opposes the second transfer roller 28.

The second transfer roller 28 transfers the toner images that have been transferred to the transfer belt 24 to the recording medium P at a second transfer position T2 between the opposing roller 39B and the second transfer roller 28. In the present exemplary embodiment, a second transfer electric field is applied between the opposing roller 39B and the second transfer roller 28 so that the toner images that have been transferred to the transfer belt 24 are transferred to the recording medium P at the second transfer position T2.

Fixing Device 16

The fixing device 16 illustrated in FIG. 1 fixes the toner images that have been transferred to the recording medium P by the second transfer roller 28 to the recording medium P. More specifically, as illustrated in FIG. 1, the fixing device 16 includes a heating roller 16A that serves as a heating member and a pressing roller 16B that serves as a pressing member. The heating roller 16A and the pressing roller 16B of the fixing device 16 respectively apply heat and pressure to the recording medium P so that the toner images on the recording medium P are fixed to the recording medium P.

Exposure Device 40

The structure of the exposure device 40 according to the present exemplary embodiment will now be described. The

exposure device 40 is an example of a light-emitting device. FIG. 2 is a perspective view illustrating the structure of the exposure device 40. FIG. 3 is a plan view illustrating the structure of the exposure device 40. FIG. 4 is a cross-sectional view illustrating the structure of the exposure device 40 (sectional view taken along line IV-IV in FIG. 2). In FIG. 2, a portion of a cleaning mechanism 60 described below is not illustrated. In FIG. 3, side coverings 45 and 46 and a container covering 47 described below are not illustrated. In FIG. 4, a portion of the cleaning mechanism 60 described below and a portion of a wire 55 are not illustrated.

The Z direction in the drawings corresponds to a depth direction of the exposure device 40, and is also a longitudinal direction of the exposure device 40 as described below. The Z direction in the drawings is also an axial direction of the corresponding photoconductor drum 32 (see FIG. 1). The X direction in the drawings corresponds to a width direction of the exposure device 40, and is also a transverse direction of the exposure device 40. The Y direction in the drawings corresponds to a height direction of the exposure device 40. As described below, the +Y direction in the drawings is a light-emitting direction in which the exposure device 40 emits light. In other words, the +Y direction in the drawings is a radiation direction in which the exposure device 40 radiates light. The depth direction, the width direction, and the height direction described above are defined to facilitate description, and therefore do not limit the structure of the exposure device 40.

Referring to FIGS. 2 and 3, the exposure device 40 extends in the axial direction of the corresponding photoconductor drum 32 (see FIG. 1), which is the Z direction, and has a length in the axial direction. In other words, the exposure device 40 has an elongated shape that extends in the Z direction. The length of the exposure device 40 in the longitudinal direction (Z direction) is greater than or equal to the length of the photoconductor drum 32 in the axial direction (Z direction).

The exposure device 40 emits light in the +Y direction (hereinafter sometimes referred to as "light-emitting direction") so that the corresponding photoconductor drum 32 (see FIG. 1) is exposed to light as described above. In FIGS. 2 and 4, for example, the exposure device 40 is oriented such that the light-emitting direction is upward. However, in practice, as illustrated in FIG. 1, the exposure device 40 emits light downward in the direction of gravity. The relationship between the light-emitting direction of the exposure device 40 and the direction of gravity is not limited, and the light-emitting direction of the exposure device 40 may be changed as appropriate. For example, the light-emitting direction of the exposure device 40 may instead be, for example, an upward direction opposite to the direction of gravity, a horizontal direction, or a direction at an angle with respect to the direction of gravity.

As illustrated in FIG. 2, the exposure device 40 includes light-emitting units 41, 42, and 43, a base 44, the side coverings 45 and 46, the container covering 47, and the cleaning mechanism 60.

Light-Emitting Units 41, 42, and 43

The light-emitting unit 41 is an example of a first light-emitting unit. The light-emitting unit 42 is an example of a second light-emitting unit. As illustrated in FIGS. 2, 3, and 4, the light-emitting units 41, 42, and 43 are provided on the base 44. More specifically, the light-emitting units 41, 42, and 43 are disposed on a surface of the base 44 facing in the +Y direction.

Each of the light-emitting units 41, 42, and 43 extends in the -Z direction, which is an example of one direction. In other words, the light-emitting units 41, 42, and 43 are elongated members having elongated shapes that extend in the Z direction. Each of the light-emitting units 41, 42, and 43 is configured to emit light through an emission surface 59. More specifically, each of the light-emitting units 41, 42, and 43 emits light in the light-emitting direction (+Y direction).

In the present exemplary embodiment, as illustrated in FIG. 3, the light-emitting units 41, 42, and 43 are arranged in a staggered pattern in plan view (that is, when viewed in the -Y direction). More specifically, the light-emitting units 43 and 42 are arranged in the Z direction with an interval therebetween, and the light-emitting unit 41 is disposed between the light-emitting units 43 and 42 in the Z direction and adjacent to the light-emitting units 43 and 42 in the +X direction.

Still more specifically, the light-emitting units 41, 42, and 43 are arranged in the following manner. The light-emitting unit 41 is located in the -Z direction with respect to the light-emitting unit 43. The light-emitting unit 41 is located in the -Z direction with respect to the light-emitting unit 43 at a position shifted from the light-emitting unit 43 in the +X direction. When viewed in the X direction, an end portion of the light-emitting unit 41 in the +Z direction overlaps an end portion of the light-emitting unit 43 in the -Z direction. Thus, when viewed in the X direction, a light emission area of the light-emitting unit 43 and a light emission area of the light-emitting unit 41 partially overlap in the Z direction. The light-emitting unit 43 and the light-emitting unit 41 do not overlap when viewed in the Z direction.

The light-emitting unit 42 is located in the -Z direction with respect to the light-emitting unit 41. The light-emitting unit 42 is located in the -Z direction with respect to the light-emitting unit 41 at a position shifted from the light-emitting unit 41 in the -X direction. When viewed in the X direction, an end portion of the light-emitting unit 42 in the +Z direction overlaps an end portion of the light-emitting unit 41 in the -Z direction. Thus, when viewed in the X direction, the light emission area of the light-emitting unit 41 and a light emission area of the light-emitting unit 42 partially overlap in the Z direction. The light-emitting unit 41 and the light-emitting unit 42 do not overlap when viewed in the Z direction. The light-emitting unit 43 and the light-emitting unit 42 overlap when viewed in the Z direction.

As illustrated in FIGS. 4 and 5, each of the light-emitting units 41, 42, and 43 includes a body 53, a light-emitting board 54, which is as an example of a light-emitting member, a driving board 57, a lens unit 50, and a lens holder 58. FIG. 5 illustrates the light-emitting unit 42 as a representative example of the light-emitting units 41, 42, and 43. The structure of the light-emitting unit 43 is similar to that of the light-emitting unit 42. The structure of the light-emitting unit 41 is obtained by inverting the structure of the light-emitting unit 42 in the left-right direction (X direction).

Referring to FIG. 4, the light-emitting board 54 has a function of emitting light in the light-emitting direction (+Y direction) and includes a substrate and plural light sources 54A arranged in the Z direction on the substrate. In the present exemplary embodiment, each light source 54A includes, for example, plural light-emitting elements. For example, each light source 54A is a light-emitting-element array including a semiconductor substrate and plural light-emitting elements arranged in the Z direction on the semiconductor substrate. In the present exemplary embodiment,

the light sources **54A**, which are the light-emitting-element arrays, are arranged in a staggered pattern along the Z direction on the substrate of the light-emitting board **54**. Each light source **54A** may be a single light-emitting element instead of the light-emitting-element array. The light-emitting elements may each be composed of, for example, a light-emitting diode, a light-emitting thyristor, or a laser element, and have a resolution of, for example, 2400 dpi when the plural light-emitting elements are arranged in the Z direction.

As illustrated in FIG. 4, the body **53** has a function of a support that supports the light-emitting board **54** at a side of the light-emitting board **54** in a direction opposite to the light-emitting direction (-Y direction). In other words, the body **53** supports the light-emitting board **54** at a back surface (surface facing in the -Y direction) of the light-emitting board **54**. As illustrated in FIG. 5, the body **53** has the shape of a rectangular parallelepiped that extends in the Z direction. More specifically, similarly to the base **44**, the body **53** is composed of a metal block made of, for example, iron, steel, or stainless steel. The body **53** may instead be composed of a metal block made of a metal other than iron, steel, or stainless steel. For example, the metal block may be made of aluminum, which has a higher thermal conductivity and a lower weight than iron, steel, or stainless steel. However, when the base **44** and the body **53** have different coefficients of thermal expansion, distortion or bending may occur. Therefore, to reduce distortion and bending, the base **44** and the body **53** may be made of the same material.

The driving board **57** is attached to a side surface of the body **53**. The driving board **57** is used to drive the light-emitting board **54**. The driving board **57** may be, for example, an application specific integrated circuit (ASIC) board. In each of the light-emitting units **42** and **43**, the driving board **57** is attached to a side surface of the body **53** facing in the +X direction. In the light-emitting unit **41**, the driving board **57** is attached to a side surface of the body **53** facing in the -X direction.

The lens unit **50** and the lens holder **58** are located in the light-emitting direction (+Y direction) with respect to the light-emitting board **54**. Similarly to the body **53**, the lens unit **50** and the lens holder **58** extend in the Z direction.

The lens unit **50** is composed of, for example, a lens array including plural lenses. The lens unit **50** is located in the light-emitting direction with respect to the light sources **54A** and faces each light source **54A** with a gap therebetween. The lens unit **50** has the emission surface **59** through which light is emitted. The emission surface **59** extends along the -Z direction. More specifically, the emission surface **59** is a surface of the lens unit **50** facing in the +Y direction, and faces the corresponding photoconductor drum **32** (see FIG. 1). The light from the light sources **54A** is incident on the lens unit **50**, and is emitted through the emission surface **59** toward a surface (that is, an outer peripheral surface) of the corresponding photoconductor drum **32** (see FIG. 1), which is an irradiation target.

The lens holder **58** has a function of holding the lens unit **50**. More specifically, the lens holder **58** clamps the lens unit **50** in the X direction such that the lens unit **50** projects from the lens holder **58** in the light-emitting direction. The lens holder **58** has fitting grooves **58C**, to which fitting portions **84C** described below are fitted, in side surfaces thereof facing in the -X and +X directions. The fitting grooves **58C** extend in the Z direction. More specifically, the fitting grooves **58C** extend through the lens holder **58** in the Z direction. In other words, the fitting grooves **58C** open in the -Z and +Z directions.

Although the body **53** is composed of a metal block in the present exemplary embodiment, the body **53** is not limited to this. For example, the body **53** may instead be composed of a metal plate. Also, the body **53** may instead be made of a resin material.

Base **44**

As illustrated in FIGS. 2 and 3, similarly to the light-emitting units **41**, **42**, and **43**, the base **44** extends in the -Z direction. In other words, the base **44** is an elongated member having an elongated shape that extends in the Z direction. More specifically, the base **44** is rectangular-parallelepiped-shaped.

The base **44** is located in a direction opposite to the light-emitting direction with respect to the light-emitting units **41**, **42**, and **43**. More specifically, the bodies **53** of the light-emitting units **41**, **42**, and **43** are attached to the base **44** at the sides of the bodies **53** in the direction opposite to the light-emitting direction. In other words, the base **44** supports the light-emitting units **41**, **42**, and **43**.

In the present exemplary embodiment, the base **44** is composed of a metal block. According to the present exemplary embodiment, the metal block does not include a general metal plate that is shaped by bending, but is a metal body having a thickness that does not substantially allow bending when shaped to serve as the base of the exposure device **40**. In one example, the metal body has a thickness (dimension in the Y direction) that is 10% or more of the width (dimension in the X direction) of the base **44**. Furthermore, the metal body may be shaped so that the thickness of the base **44** is 20% or more and 100% or less of the width of the base **44**.

A wide image forming apparatus according to the related art is used to output a monochrome image, and the required image quality is lower than that of a full-color printer for commercial printing. The image forming apparatus **10** according to the present exemplary embodiment is a full-color printer for commercial printing, and is required to form a high-quality image. Accordingly, a metal block that is more rigid than a metal plate is used to reduce the influence of bending of the base **44** on the image quality.

The base **44** may be made of, for example, iron, steel, or stainless steel. The base **44** may instead be composed of a metal block made of a material other than iron, steel, or stainless steel. For example, aluminum, which has a higher thermal conductivity and a lower weight than iron, steel, or stainless steel, may instead be used. In the present exemplary embodiment, heat generated by the light sources **54A** is dissipated through the body **53**. Therefore, rigidity is prioritized over thermal conductivity and weight, and the base **44** is made of iron, steel, or stainless steel.

The thickness of the base **44** in the light-emitting direction (+Y direction) may be greater than the thickness of the body **53** of each of the light-emitting units **41**, **42**, and **43** in the light-emitting direction (+Y direction). In such a case, the rigidity of the base **44** (flexural rigidity in the Y direction) is greater than the rigidity of each of the light-emitting units **41**, **42**, and **43**. The thickness of the base **44** in the light-emitting direction (+Y direction) may be 5 mm or more, 10 mm or more, or 20 mm or more.

Although the base **44** is composed of a metal block in the present exemplary embodiment, the base **44** is not limited to this. For example, the base **44** may instead be composed of a metal plate. Also, the base **44** may instead be made of a resin material.

Container Covering **47**

As illustrated in FIGS. 2 and 4, the container covering **47** is a cover that contains wires **55** that are electrically con-

nected to the light-emitting units 41, 42, and 43 (more specifically, to the driving boards 57). The container covering 47 is attached to a portion of the base 44 in the -Y direction. In the present exemplary embodiment, the container covering 47 is U-shaped in cross section and opens in the +Y direction. End portions of the container covering 47 in the +Y direction are fastened to surfaces of the base 44 at both sides (sides in the -X and +X directions) of the base 44 with plural fastening members 49. The fastening members 49 have helical grooves that enable the fastening members 49 to be fastened. In other words, the fastening members 49 are members having a screw mechanism, and may be, for example, screws or bolts. As illustrated in FIG. 4, each wire 55 extends through a passage 44C, which extends through the base 44 in the Y direction, to the outside of the base 44 in the -Y direction.

Side Coverings 45 and 46

The side coverings 45 and 46 illustrated in FIGS. 2 and 4 are examples of a removably attachable member. The side coverings 45 and 46 are coverings that cover the light-emitting units 41, 42, and 43 from the sides thereof. The side coverings 45 and 46 are plate-shaped and extend from the base 44 in the light-emitting direction.

The side coverings 45 and 46 are removably attached to the base 44 at one side (side in the -X direction) and the other side (side in the +X direction), respectively, of the base 44 in the width direction. More specifically, portions of the side coverings 45 and 46 in the -Y direction are removably attached to both sides of the base 44 in the transverse direction (X direction). Still more specifically, the side coverings 45 and 46 are removably fastened with fastening members 48. The fastening members 48 have helical grooves that enable the fastening members 48 to be fastened. In other words, the fastening members 48 are members having a screw mechanism, and may be, for example, screws or bolts.

Cleaning Mechanism 60

Referring to FIG. 3, the cleaning mechanism 60 cleans the emission surfaces 59 (see also FIGS. 4 and 5) of the light-emitting units 41, 42, and 43. The emission surface 59 of the light-emitting unit 41 is an example of a first emission surface. The emission surface 59 of the light-emitting unit 42 is an example of a second emission surface.

As illustrated in FIG. 3, the cleaning mechanism 60 includes cleaning units 61, 62, and 63, transmission parts 64, 65, and 66, extending parts 67 and 68, a coupling part 69, and support parts 71, 72, and 73.

Cleaning Units 61, 62, and 63

The cleaning unit 61 illustrated in FIG. 3 is an example of a cleaning unit or a first cleaning unit. The cleaning unit 62 illustrated in FIG. 3 is an example of a second cleaning unit. The cleaning units 61, 62, and 63 are members that clean the emission surfaces 59 of the light-emitting units 41, 42, and 43, respectively. As illustrated in FIG. 3, the cleaning units 61, 62, and 63 are respectively provided on the light-emitting units 41, 42, and 43. The cleaning unit 61 and each of the cleaning units 62 and 63 have similar structures except that the structures thereof are inverted with respect to each other in the left-right direction (X direction). Therefore, in the following description, the structure of the cleaning unit 61 will be described, and description of the structure of the cleaning units 62 and 63 will be omitted as appropriate.

The cleaning unit 61 is capable of moving in the -Z and +Z directions (hereinafter referred to as “-+Z directions”) to clean the corresponding emission surface 59. The +Z direc-

tion is an example of an opposite direction. FIG. 3 illustrates the cleaning units 61, 62, and 63 that are positioned furthest in the +Z direction.

More specifically, as illustrated in FIGS. 6 and 7, the cleaning unit 61 includes a contact part 82 and a support part 84. The contact part 82 comes into contact with the emission surface 59. In other words, the contact part 82 cleans the emission surface 59 by moving in the -+Z directions. More specifically, the contact part 82 moves in the -+Z directions to clean the emission surface 59 by wiping the emission surface 59.

The contact part 82 is made of, for example, an elastic material, such as urethane rubber. The contact part 82 is plate-shaped. The material and shape of the contact part 82 may be known material and shape. The contact part 82 is attached to an opposing portion 84A of the support part 84 described below.

The support part 84 supports the contact part 82. More specifically, the support part 84 includes the opposing portion 84A, a pair of side portions 84B, and a pair of fitting portions 84C.

The opposing portion 84A is located in the light-emitting direction (+Y direction) with respect to the emission surface 59. More specifically, the opposing portion 84A opposes the emission surface 59 with a gap therebetween. The opposing portion 84A is plate-shaped and has a thickness substantially in the Y direction.

The pair of side portions 84B extend diagonally downward from the opposing portion 84A in FIG. 7, and then extend in the -Y direction to positions on the sides of the lens holder 58 in the -X and +X directions.

The pair of fitting portions 84C project toward the lens holder 58 from the side portions 84B, and are fitted to the fitting grooves 58C. The fitting portions 84C are guided along the fitting grooves 58C so that the cleaning unit 61 is movable in the -+Z directions.

Transmission Parts 64, 65, and 66

The transmission part 64 illustrated in FIG. 3 is an example of a transmission part or a first transmission part. The transmission part 65 illustrated in FIG. 3 is an example of a second transmission part. As illustrated in FIG. 3, the transmission parts 64, 65, and 66 respectively extend from the cleaning units 61, 62, and 63 in the -Z direction, and have a function of transmitting a moving force for moving the cleaning units 61, 62, and 63 to the cleaning units 61, 62, and 63. More specifically, the transmission parts 64, 65, and 66 are composed of solid cylindrical rods that extend from the cleaning units 61, 62, and 63 in the -Z direction.

As illustrated in FIGS. 6 and 7, the transmission part 64 is located in the +X direction and in the -Y direction with respect to the cleaning unit 61. More specifically, the transmission part 64 is located in the +X direction with respect to the light-emitting unit 41 (more specifically, the body 53). One end (more specifically, end in the +Z direction) of the transmission part 64 is attached to one of the side portions 84B of the support part 84 of the cleaning unit 61 with an attachment part 64A.

As described above, the transmission part 64 is located in the +X direction with respect to the cleaning unit 61. Referring to FIG. 7, the transmission parts 65 and 66 are located in the -X direction with respect to the cleaning units 62 and 63, respectively. Except for this point, the structure of the transmission parts 65 and 66 is similar to that of the transmission part 64. Namely, the transmission parts 65 and 66 are located in the -X direction and in the -Y direction with respect to the cleaning units 62 and 63, respectively. More specifically, each of the transmission parts 65 and 66

11

is located in the $-X$ direction with respect to the corresponding one of the light-emitting units 42 and 43 (more specifically, the body 53). One end (more specifically, end in the $+Z$ direction) of each of the transmission parts 65 and 66 is attached to one of the side portions 84B of the support part 84 of the corresponding one of the cleaning units 62 and 63 with an attachment part 65C. Thus, in the present exemplary embodiment, the transmission parts 65 and 66 are disposed at a position shifted from the transmission part 64 in the X direction (width direction). The structure of the cleaning unit 63 and the attachment structure between the cleaning unit 63 and the transmission part 66 are similar to the structure of the cleaning unit 62 and the attachment structure between the cleaning unit 62 and the transmission part 65. In FIG. 7, only the structure of the cleaning unit 62 and the attachment structure between the cleaning unit 62 and the transmission part 65 are illustrated.

Referring to FIG. 3, when the cleaning units 61, 62, and 63 are positioned furthest in the $+Z$ direction, the transmission parts 64, 65, and 66 extend in the $-Z$ direction from the cleaning units 61, 62, and 63 to the ends of the light-emitting units 41, 42, and 43.

Coupling Part 69

The coupling part 69 illustrated in FIG. 3 is composed of a solid cylindrical rod that couples the transmission part 65 and the transmission part 66 to each other and that is integrated with the transmission parts 65 and 66. Thus, the moving force of the transmission part 65 is transmitted to the transmission part 66 through the coupling part 69.

Extending Parts 67 and 68

The extending part 67 illustrated in FIG. 3 is an example of an extending part or a first extending part. The extending part 68 illustrated in FIG. 3 is an example of a second extending part. The extending parts 67 and 68 respectively extend from the transmission parts 64 and 65 in the $-Z$ direction and have a function of elongating the transmission parts 64 and 65.

In the present exemplary embodiment, the extending parts 67 and 68 are composed of solid cylindrical rods that are integrated with the transmission parts 64 and 65, respectively. Thus, in the cleaning mechanism 60, the transmission part 66, the coupling part 69, the transmission part 65, and the extending part 68 are integrated in the form of a solid cylindrical rod. The transmission part 64 and the extending part 67 are integrated in the form of a solid cylindrical rod. Thus, the cleaning mechanism 60 includes a pair of solid cylindrical rods. The shape of the rods is not limited to a solid cylindrical shape, and may instead be, for example, a hollow cylindrical shape, a prism shape, or a rectangular tubular shape. The cross-sectional shape of the rods is not limited to a circular shape, and may instead be, for example, a polygonal shape or other shapes. The transmission part 66, the coupling part 69, the transmission part 65, and the extending part 68 may instead be composed of separate parts. The transmission part 64 and the extending part 67 may instead be composed of separate parts.

When the cleaning units 61 and 62 are positioned furthest in the $+Z$ direction, the extending parts 67 and 68 extend in the $-Z$ direction from the ends of the light-emitting units 41 and 42 in the $-Z$ direction.

When the cleaning units 62 and 63 are positioned furthest in the $+Z$ direction, an end of the extending part 68 in the $-Z$ direction is located further in the $-Z$ direction than one end 41A (end in the $-Z$ direction) of the light-emitting unit 41. More specifically, when the cleaning units 62 and 63 are positioned furthest in the $+Z$ direction, the end of the extending part 68 in the $-Z$ direction is located further in the

12

$-Z$ direction than one end 42A (end in the $-Z$ direction) of the light-emitting unit 42. Still more specifically, when the cleaning units 62 and 63 are positioned furthest in the $+Z$ direction, the end of the extending part 68 in the $-Z$ direction is located further in the $-Z$ direction than one end 44A (end in the $-Z$ direction) of the base 44.

When the cleaning unit 61 is positioned furthest in the $+Z$ direction, an end of the extending part 67 in the $-Z$ direction is located further in the $-Z$ direction than a midpoint CA between the one end 41A (end in the $-Z$ direction) of the light-emitting unit 41 and the one end 42A (end in the $-Z$ direction) of the light-emitting unit 42.

More specifically, when the cleaning unit 61 is positioned furthest in the $+Z$ direction, the end of the extending part 67 in the $-Z$ direction is located further in the $-Z$ direction than the one end 42A (end in the $-Z$ direction) of the light-emitting unit 42. Still more specifically, when the cleaning unit 61 is positioned furthest in the $+Z$ direction, the end of the extending part 67 in the $-Z$ direction is located further in the $-Z$ direction than the one end 44A (end in the $-Z$ direction) of the base 44.

Furthermore, when the cleaning unit 61 is positioned furthest in the $+Z$ direction and when the cleaning unit 62 is positioned furthest in the $+Z$ direction, the end of the extending part 67 in the $-Z$ direction is located further in the $-Z$ direction than the end of the transmission part 65 in the $-Z$ direction. More specifically, when the cleaning unit 61 is positioned furthest in the $+Z$ direction and when the cleaning unit 62 is positioned furthest in the $+Z$ direction, the end of the extending part 67 in the $-Z$ direction and the end of the extending part 68 in the $-Z$ direction are at the same position in the Z direction.

A holding part 90 (more specifically, a handle) to be held by an operator is provided at the ends of the extending parts 67 and 68 in the $-Z$ direction. More specifically, the holding part 90 extends in the X direction from the end of the extending part 67 in the $-Z$ direction to the end of the extending part 68 in the $-Z$ direction. Still more specifically, an end of the holding part 90 in the $+X$ direction is attached to the end of the extending part 67 in the $-Z$ direction, and an end of the holding part 90 in the $-X$ direction is attached to the end of the extending part 68 in the $-Z$ direction.

The operator manually operates the holding part 90 so that the moving force is generated, and the generated moving force is transmitted to the cleaning unit 61 through the extending part 67 and the transmission part 64. The moving force is transmitted to the cleaning unit 62 through the extending part 68 and the transmission part 65. The moving force is also transmitted to the cleaning unit 63 through the extending part 68, the transmission part 65, the coupling part 69, and the transmission part 66.

Thus, in the present exemplary embodiment, the holding part 90 is provided as a common holding part for the extending parts 67 and 68. Therefore, when the holding part 90 is operated, the cleaning units 61, 62, and 63 are moved together. The extending parts 67 and 68 may instead be provided with respective holding parts. In such a case, the cleaning unit 61 and the pair of cleaning units 62 and 63 are moved independently of each other.

60 Support Parts 71, 72, and 73

As illustrated in FIG. 3, the support part 71 supports the extending part 67 such that the extending part 67 is movable in the $-+Z$ directions. The support part 73 supports the coupling part 69 such that the coupling part 69 is movable in the $-+Z$ directions. The support part 72 supports both of the extending parts 67 and 68 such that the extending parts 67 and 68 are movable in the $-+Z$ directions. The support

parts 71, 72, and 73 are provided on the base 44 and are not fixed to the side coverings 45 and 46.

More specifically, as illustrated in FIG. 8, the support part 71 includes a bottom plate 75 and a side plate 76, and is L-shaped when viewed in the X direction. The bottom plate 75 is attached to the base 44 with a fastening member. The fastening member has a helical groove that enables the fastening member to be fastened. In other words, the fastening member is a member having a screw mechanism, and may be, for example, a screw or a bolt. The extending part 67 is supported by the side plate 76 such that the extending part 67 is movable in the +Z directions. The side plate 76 of the support part 71 supports the extending part 67 at a position near an end thereof in the +X direction. The structure of the support part 73 is similar to that of the support part 71, and includes a bottom plate 75 and a side plate 76. The side plate 76 of the support part 73 supports the coupling part 69 at a position near an end thereof in the -X direction.

The structure of the support part 72 is also similar to that of the support part 71, and includes a bottom plate 75 and a side plate 76, as illustrated in FIG. 9. The support part 72 has an elongated shape that extends in the X direction. The side plate 76 of the support part 72 supports the extending part 67 at a position near an end thereof in the +X direction, and supports the extending part 68 at a position near an end thereof in the -X direction.

As illustrated in FIG. 3, the support part 71 is located further in the -Z direction than the one end 41A (end in the -Z direction) of the light-emitting unit 41. More specifically, the support part 71 is located between the one end 41A of the light-emitting unit 41 and the midpoint CA. The support part 71 is disposed on the base 44 at a position such that at least a portion thereof overlaps the light-emitting unit 41 when viewed in the Z direction. The support part 71 is also disposed on the base 44 at a position such that the support part 71 overlaps the light-emitting unit 42 when viewed in the X direction.

The support part 73 is located further in the -Z direction than one end 43A (end in the -Z direction) of the light-emitting unit 43. More specifically, the support part 73 is located between the one end 43A of the light-emitting unit 43 and the one end 42B (end in the +Z direction) of the light-emitting unit 42. The support part 73 is disposed on the base 44 at a position such that at least a portion thereof overlaps the light-emitting units 43 and 42 when viewed in the Z direction. The support part 73 is also disposed on the base 44 at a position such that the support part 73 overlaps the light-emitting unit 41 when viewed in the X direction.

The support part 72 is located further in the -Z direction than the one end 41A (end in the -Z direction) of the light-emitting unit 41. More specifically, the support part 72 is located further in the -Z direction than the midpoint CA. Still more specifically, the support part 72 is located further in the -Z direction than the one end 42A (end in the -Z direction) of the light-emitting unit 42.

The support part 72 is disposed on the base 44 at a position such that at least a portion thereof overlaps at least one of the light-emitting unit 41 and the light-emitting unit 42 when viewed in the Z direction. More specifically, in the present exemplary embodiment, the support part 72 is disposed on the base 44 at a position such that at least a portion thereof overlaps both the light-emitting unit 41 and the light-emitting unit 42 when viewed in the Z direction. Still more specifically, the support part 72 is disposed on the base 44 to extend from a position located in the +X direction with

respect to the light-emitting unit 41 to a position located in the -X direction with respect to the light-emitting unit 42.

Although the support part 72 supports both of the extending parts 67 and 68, the support part 72 is not limited to this. The support part 72 may instead be composed of two support parts that independently support respective ones of the extending parts 67 and 68.

Other Structures of Cleaning Mechanism 60

As illustrated in FIGS. 3 and 6, the cleaning mechanism 60 includes a projecting part 94 that projects from the transmission part 64 in the +Z direction. The projecting part 94 is composed of a solid cylindrical rod that is integrated with the transmission part 64 and the extending part 67. The projecting part 94 comes into contact with a restricting part 95 so that movement thereof in the +Z direction is restricted.

Thus, the cleaning unit 61 is positioned at the end of the light-emitting unit 41 in the +Z direction at a position such that the fitting portions 84C of the cleaning unit 61 are not separated from the fitting grooves 58C, which are formed in the light-emitting unit 41 so as to open in the +Z direction. When the cleaning unit 61 is positioned at the end of the light-emitting unit 41 in the +Z direction, the cleaning unit 61 is positioned furthest in the +Z direction. A restricted part (not shown) provided on at least one of the transmission part 64 and the extending part 67 comes into contact with a restricting part (not shown) so that movement thereof in the -Z direction is restricted. The restricting part may be one of the support parts 71 and 72.

As illustrated in FIG. 3, the cleaning mechanism 60 includes a projecting part 96 that projects from the transmission part 66 in the +Z direction. The projecting part 96 is composed of a solid cylindrical rod that is integrated with the transmission part 66, the coupling part 69, the transmission part 65, and the extending part 68. The projecting part 96 comes into contact with a restricting part 97 so that movement thereof in the +Z direction is restricted.

Thus, the cleaning units 62 and 63 are respectively positioned at the ends of the light-emitting units 42 and 43 in the +Z direction at positions such that the fitting portions 84C of the cleaning units 62 and 63 are not separated from the fitting grooves 58C, which are formed in the light-emitting units 42 and 43 so as to open in the +Z direction. When the cleaning units 62 and 63 are positioned at the ends of the light-emitting units 42 and 43 in the +Z direction, the cleaning units 62 and 63 are positioned furthest in the +Z direction. A restricted part (not shown) provided on at least one of the transmission part 66, the coupling part 69, the transmission part 65, and the extending part 68 comes into contact with a restricting part (not shown) so that movement thereof in the -Z direction is restricted. The restricting part may be one of the support parts 72 and 73.

Supplemental Description

In the present exemplary embodiment, as described above, the image forming apparatus 10 is capable of forming an image on a recording medium P having a large medium width (that is, length in the Z direction). More specifically, as described above, the image forming apparatus 10 is capable of forming an image on a recording medium P having a medium width of, for example, a transversely fed B2-size sheet (that is, 728 mm).

To enable formation of an image on the recording medium P having a large width, in the present exemplary embodiment, the exposure device 40 includes plural light-emitting units (light-emitting units 41, 42, and 43) as described above. The light-emitting units are long in the Z direction, and are arranged in the Z direction.

15

An example of an existing image forming apparatus that forms an image on a recording medium P having a large width is a low-speed image forming apparatus that forms a monochrome image of, for example, a design plan. This image forming apparatus includes a single toner-image forming unit, and the number of other components is small. Therefore, the exposure device 40 is accessible in a direction other than the Z direction (that is, in the Y direction or the X direction). Therefore, a user may directly and manually clean the emission surface 59 with a cleaning member, such as cloth, by accessing the exposure device 40 in the Y direction or the X direction. Thus, no cleaning mechanism is necessary.

In contrast, in an image forming apparatus that forms a multiple-color image as in the present exemplary embodiment (in particular, in a full-color printer for commercial printing required to print a high-quality image), the number of components is greater than that in the monochrome image forming apparatus according to the related art. Therefore, the exposure device 40 is not easily accessible in the Y direction or the X direction. Accordingly, a cleaning mechanism capable of cleaning the emission surface 59 by accessing the exposure device 40 in the Z direction is required.

Operation of Present Exemplary Embodiment

The operation of the present exemplary embodiment will now be described.

As described above, according to the present exemplary embodiment, when the cleaning unit 61 is positioned furthest in the +Z direction as illustrated in FIG. 3, the end of the extending part 67 in the -Z direction is located further in the -Z direction than the midpoint CA between the one end 41A (end in the -Z direction) of the light-emitting unit 41 and the one end 42A (end in the -Z direction) of the light-emitting unit 42.

In the present exemplary embodiment, when the cleaning unit 61 is positioned furthest in the +Z direction, the end of the extending part 67 in the -Z direction is located further in the -Z direction than the one end 42A (end in the -Z direction) of the light-emitting unit 42.

In addition, in the present exemplary embodiment, when the cleaning unit 61 is positioned furthest in the +Z direction, the end of the extending part 67 in the -Z direction is located further in the -Z direction than the one end 44A (end in the -Z direction) of the base 44.

In the present exemplary embodiment, the support part 71 supports the extending part 67 such that the extending part 67 is movable in the -+Z directions. The support part 72 supports both of the extending parts 67 and 68 such that the extending parts 67 and 68 are movable in the -+Z directions.

The support part 73 supports the coupling part 69 such that the coupling part 69 is movable in the -+Z directions.

In the present exemplary embodiment, the support part 72 is located further in the -Z direction than the midpoint CA.

In the present exemplary embodiment, the support part 72 is located further in the -Z direction than the one end 42A (end in the -Z direction) of the light-emitting unit 42.

In the present exemplary embodiment, the support parts 71, 72, and 73 are provided on the base 44.

In the present exemplary embodiment, the support parts 71, 72, and 73 are not fixed to the side coverings 45 and 46.

In the present exemplary embodiment, the support part 71 is disposed on the base 44 at a position such that at least a portion thereof overlaps the light-emitting unit 41 when viewed in the Z direction.

In the present exemplary embodiment, the support part 72 is disposed on the base 44 at a position such that at least a

16

portion thereof overlaps both the light-emitting unit 41 and the light-emitting unit 42 when viewed in the Z direction.

In the present exemplary embodiment, the support part 73 is disposed on the base 44 at a position such that at least a portion thereof overlaps the light-emitting units 43 and 42 when viewed in the Z direction.

In the present exemplary embodiment, as described above, the support part 72 supports both of the extending parts 67 and 68 such that the extending parts 67 and 68 are movable in the -+Z directions.

In the present exemplary embodiment, the support part 73 is disposed between the light-emitting unit 43 and the light-emitting unit 42.

In the present exemplary embodiment, the body 53 of each of the light-emitting units 41, 42, and 43 is composed of a metal block made of, for example, iron, steel, or stainless steel. In the present exemplary embodiment, the base 44 is composed of a metal block made of, for example, iron, steel, or stainless steel.

Supplemental Description Regarding Exposure Device 40

In the above-described exemplary embodiment, the light-emitting unit 41 is described as an example of a first light-emitting unit, the cleaning unit 61 as an example of a cleaning unit or a first cleaning unit, the transmission part 64 as an example of a transmission part or a first transmission part, and the extending part 67 as an example of an extending part or a first extending part. However, the exposure device 40 is not limited to this.

For example, the light-emitting unit 43 may be regarded as an example of a first light-emitting unit, the cleaning unit 63 as an example of a cleaning unit or a first cleaning unit, the transmission part 66 as an example of a transmission part or a first transmission part, and a section composed of the coupling part 69, the transmission part 65, and the extending part 68 as an example of an extending part or a first extending part. In this case (hereinafter referred to as case A), the light-emitting unit 41 may be regarded as an example of a second light-emitting unit, the cleaning unit 61 as an example of a second cleaning unit, the transmission part 64 as an example of a second transmission part, and the extending part 67 as an example of a second extending part.

Alternatively, in case A, the light-emitting unit 42 may be regarded as an example of a second light-emitting unit, the cleaning unit 62 as an example of a second cleaning unit, the transmission part 65 as an example of a second transmission part, and the extending part 68 as an example of a second extending part.

In case A, when the cleaning unit 63 is positioned furthest in the +Z direction as illustrated in FIG. 3, an end in the -Z direction of the extending part composed of the coupling part 69, the transmission part 65, and the extending part 68 is located further in the -Z direction than a midpoint CB between the one end 43A (end in the -Z direction) of the light-emitting unit 43 and the one end 41A (end in the -Z direction) of the light-emitting unit 41. In case A, when the cleaning unit 63 is positioned furthest in the +Z direction, the end in the -Z direction of the extending part composed of the coupling part 69, the transmission part 65, and the extending part 68 is located further in the -Z direction than a midpoint CC between the one end 43A (end in the -Z direction) of the light-emitting unit 43 and the one end 42A (end in the -Z direction) of the light-emitting unit 42.

In case A, the support part 72 that supports the extending part composed of the coupling part 69, the transmission part 65, and the extending part 68 is located further in the -Z

direction than the midpoint CB. More specifically, the support part 72 is located further in the -Z direction than the midpoint CC.

Modifications

In the present exemplary embodiment, although the light-emitting units 41, 42, and 43 are disposed on the base 44, the arrangement is not limited to this. For example, as illustrated in FIG. 10, only the light-emitting units 41 and 42 may be disposed on the base 44. In this case, the cleaning unit 63, the transmission part 66, the coupling part 69, and the support part 73 may be omitted. The length of the base 44 in the Z direction may be a length corresponding to the lengths of the two light-emitting units 41 and 42 in the Z direction. The projecting part 96 is provided on the transmission part 65.

Alternatively, for example, only the light-emitting units 41 and 43 may be disposed on the base 44. In such a case, the cleaning unit 62 may be omitted. The length of the base 44 in the Z direction may be a length corresponding to the lengths of the two light-emitting units 41 and 43. Also, a light-emitting unit other than the light-emitting units 41, 42, and 43 may be additionally provided on the base 44.

In the present exemplary embodiment, when the cleaning unit 61 is positioned furthest in the +Z direction, the end of the extending part 67 in the -Z direction is located further in the -Z direction than the one end 44A (end in the -Z direction) of the base 44. However, the extending part 67 is not limited to this. For example, when the cleaning unit 61 is positioned furthest in the +Z direction, the end of the extending part 67 in the -Z direction may be located further in the +Z direction than the one end 42A (end in the -Z direction) of the light-emitting unit 42 and in the -Z direction with respect to the midpoint CA. Alternatively, for example, when the cleaning unit 61 is positioned furthest in the +Z direction, the end of the extending part 67 in the -Z direction may be located further in the +Z direction than the one end 44A (end in the -Z direction) of the base 44 and further in the -Z direction than the one end 42A (end in the -Z direction) of the light-emitting unit 42.

In the present exemplary embodiment, the support part 71 supports the extending part 67 such that the extending part 67 is movable in the -+Z directions. In the present exemplary embodiment, the support part 72 supports both of the extending parts 67 and 68 such that the extending parts 67 and 68 are movable in the -+Z directions. However, the extending parts 67 and 68 are not limited to this. For example, the extending parts 67 and 68 may not be supported.

In the present exemplary embodiment, the support part 73 supports the coupling part 69 such that the coupling part 69 is movable in the -+Z directions. However, the coupling part 69 is not limited to this. For example, the coupling part 69 may not be supported.

In the present exemplary embodiment, the support parts 71, 72, and 73 are provided on the base 44. However, the support parts 71, 72, and 73 are not limited to this. For example, the support parts 71, 72, and 73 may instead be provided on a member other than the base 44.

In the present exemplary embodiment, the support parts 71, 72, and 73 are not fixed to the side coverings 45 and 46. However, the support parts 71, 72, and 73 are not limited to this. For example, the support parts 71, 72, and 73 may be attached to the side coverings 45 and 46.

In the present exemplary embodiment, the support part 71 is disposed on the base 44 at a position such that at least a portion thereof overlaps the light-emitting unit 41 when viewed in the Z direction. However, the support part 71 is

not limited to this. For example, the support part 71 may instead be disposed on the base 44 at a position such that the entirety thereof is displaced from the light-emitting unit 41 when viewed in the Z direction.

5 In the present exemplary embodiment, the support part 72 is disposed on the base 44 at a position such that at least a portion thereof overlaps both the light-emitting unit 41 and the light-emitting unit 42 when viewed in the Z direction. However, the support part 72 is not limited to this. For example, the support part 72 may be instead disposed on the base 44 at a position such that the entirety thereof is displaced from the light-emitting unit 41 and the light-emitting unit 42 when viewed in the Z direction.

10 In the present exemplary embodiment, the support part 73 is disposed on the base 44 at a position such that at least a portion thereof overlaps the light-emitting units 43 and 42 when viewed in the Z direction. However, the support part 73 is not limited to this. For example, the support part 73 may instead be disposed on the base 44 at a position such that the entirety thereof is displaced from the light-emitting units 42 and 43 when viewed in the Z direction.

15 In the present exemplary embodiment, the support part 72 supports both of the extending parts 67 and 68 such that the extending parts 67 and 68 are movable in the -+Z directions. 20 However, the extending parts 67 and 68 are not limited to this. For example, the extending parts 67 and 68 may instead be supported by different support parts.

Second Exemplary Embodiment

30 FIG. 11 illustrates a rendering apparatus 150 including a light-emitting device 152 according to a second exemplary embodiment. Components having the same structures as those in the first exemplary embodiment are denoted by the same reference signs, and description thereof is omitted as appropriate.

35 As illustrated in FIG. 11, the rendering apparatus 150 includes the light-emitting device 152 and a cylindrical member 154. The cylindrical member 154 extends in the longitudinal direction of the light-emitting device 152 and rotates in a circumferential direction.

40 The light-emitting device 152 has the same structure as that of the exposure device 40 according to the first exemplary embodiment. More specifically, the light-emitting device 152 includes a base 44 that extends in the Z direction and light-emitting units 41, 42, and 43.

45 The cylindrical member 154 includes a cylindrical portion 154A and a shaft portion 154B that projects from both sides of the cylindrical portion 154A. The shaft portion 154B is 50 rotatably supported by a frame (not illustrated). The shaft portion 154B is rotated to rotate the cylindrical portion 154A in the circumferential direction.

55 In the rendering apparatus 150, the cylindrical member 154 is rotated while the region 156A of the substrate 156 in which the photosensitive material is provided is irradiated with light emitted from the light-emitting device 152 in a predetermined pattern. Thus, the predetermined pattern is 60 formed in the region 156A of the substrate 156 in which the photosensitive material is provided. After that, the substrate

65 is irradiated with light emitted from the light-emitting device 152 in a predetermined pattern. Thus, the predetermined pattern is formed in the region 156A of the substrate 156 in which the photosensitive material is provided. After that, the substrate

156 is developed to obtain a printing plate for use by an offset printer. In this case, a laser device, for example, may be used as a light source of the rendering apparatus **150**.

The above-described light-emitting device **152** has the same operation and effects as those of the exposure device **40** according to the first exemplary embodiment.

In the rendering apparatus **150** according to the second exemplary embodiment, the substrate **156** attached to the cylindrical portion **154A** of the cylindrical member **154** is irradiated with light emitted from the light-emitting device **152**. However, the present disclosure is not limited to this structure. For example, the substrate may be disposed on a flat plate-shaped table and irradiated with light from the light-emitting device **152** while the light-emitting device **152** and the table are moved relative to each other in a direction crossing the one direction of the light-emitting device **152**.

In the rendering apparatus **150** according to the second exemplary embodiment, the substrate **156** is a plate for CTP used in a plate making process for offset printing, and the region **156A** of the substrate **156** in which the photosensitive material is provided is irradiated with light from the light-emitting device **152**. However, the rendering apparatus **150** is not limited to this. For example, the light-emitting device and the rendering apparatus described above may instead be used in an exposure process for manufacturing a printed wiring board (PWB). For example, a substrate to which a photosensitive material, such as photoresist, is applied may be subjected to a process of directly forming a pattern on the substrate without using a photomask to manufacture a printed wiring board. The substrate that is used may be a rigid substrate or a flexible substrate. When a flexible substrate is used, the substrate may be fixed to the cylindrical member **154** illustrated in FIG. 11, and the pattern may be formed while the cylindrical member **154** is rotated.

The light-emitting device and the rendering apparatus described above may be used to process a component by photolithography. For example, the light-emitting device and the rendering apparatus may be used in formation of a color filter in a process of manufacturing a liquid crystal display (LCD); exposure of a dry film resist (DFR) in a process of manufacturing a thin film transistor (TFT); exposure of a dry film resist (DFR) in a process of manufacturing a plasma display panel (PDP); exposure of a photosensitive material, such as photoresist, in a process of manufacturing a semiconductor device; exposure of a photosensitive material, such as photoresist, in a process of manufacturing a printing plate; or exposure of a photosensitive material in a process of manufacturing a timepiece component. Here, photolithography is a technology for exposing a surface of an object on which a photosensitive material is provided to patterned light to form a pattern including exposed and unexposed portions.

The light-emitting device and the rendering apparatus described above are applicable to both a photon-mode photosensitive material, on which information is recorded directly by exposure to light, and a heat-mode photosensitive material, on which information is recorded by heat generated as a result of exposure to light. The light source of the rendering apparatus **150** may be, for example, an LED device or a laser device depending on the object exposed to light.

The light-emitting device is applicable to various devices, such as a light source of a distance measurement device that measures a distance, a light source of a display device, such as a laser projector, or a drying device that dries ink by irradiating the ink with light in an inkjet recording apparatus.

The present disclosure is not limited to the above-described exemplary embodiments, and various modifications, alterations, and improvements are possible without departing from the spirit of the present disclosure. For example, the above-described modifications may be applied in combinations with each other as appropriate.

The foregoing description of the exemplary embodiments of the present disclosure has been provided for the purposes of illustration and description. It is not intended to be exhaustive or to limit the disclosure to the precise forms disclosed. Obviously, many modifications and variations will be apparent to practitioners skilled in the art. The embodiments were chosen and described in order to best explain the principles of the disclosure and its practical applications, thereby enabling others skilled in the art to understand the disclosure for various embodiments and with the various modifications as are suited to the particular use contemplated. It is intended that the scope of the disclosure be defined by the following claims and their equivalents.

What is claimed is:

1. A light-emitting device comprising:
a first light-emitting unit that extends in one direction and that has a first emission surface that emits light located along the one direction;
a second light-emitting unit that is located in the one direction with respect to the first light-emitting unit, that extends in the one direction, and that has a second emission surface that emits light located along the one direction;
a cleaning unit that is configured to move in the one direction and an opposite direction to the one direction to clean the first emission surface;
a transmission part that extends from the cleaning unit in the one direction and that transmits a moving force for moving the cleaning unit to the cleaning unit; and
an extending part that extends from the transmission part in the one direction to elongate the transmission part, wherein when the cleaning unit is positioned furthest in the opposite direction, an end of the extending part in the one direction is located further in the one direction than a midpoint between an end of the first light-emitting unit in the one direction and an end of the second light-emitting unit in the one direction, wherein the cleaning unit is configured to move relative to the transmission part and the extending part in the one direction and the opposite direction, thereby cleaning the first emission surface.

2. The light-emitting device according to claim 1, wherein when the cleaning unit is positioned furthest in the opposite direction, the end of the extending part in the one direction is located further in the one direction than the end of the second light-emitting unit in the one direction.

3. The light-emitting device according to claim 2, further comprising:

a base located in a direction opposite to a light-emitting direction, in which the first light-emitting unit emits light, with respect to the first light-emitting unit, the base having the first light-emitting unit and the second light-emitting unit placed thereon,
wherein when the cleaning unit is positioned furthest in the opposite direction, the end of the extending part in the one direction is located further in the one direction than the end of the base in the one direction.

4. The light-emitting device according to claim 3, further comprising:

a support part that supports the extending part.

21

5. The light-emitting device according to claim 4, wherein the support part is located further in the one direction than the midpoint between the end of the first light-emitting unit in the one direction and the end of the second light-emitting unit in the one direction.

6. The light-emitting device according to claim 5, wherein the support part is located further in the one direction than the end of the second light-emitting unit in the one direction.

7. The light-emitting device according to claim 4, wherein the support part is provided on the base.

8. The light-emitting device according to claim 2, further comprising:

a support part that supports the extending part.

9. The light-emitting device according to claim 8, wherein the support part is located further in the one direction than the midpoint between the end of the first light-emitting unit in the one direction and the end of the second light-emitting unit in the one direction.

10. The light-emitting device according to claim 9, wherein the support part is located further in the one direction than the end of the second light-emitting unit in the one direction.

11. The light-emitting device according to claim 8, further comprising:

a base located in a direction opposite to a light-emitting direction, in which the first light-emitting unit emits light, with respect to the first light-emitting unit, the base having the first light-emitting unit and the second light-emitting unit placed thereon,

wherein the support part is provided on the base.

12. The light-emitting device according to claim 1, further comprising:

a support part that supports the extending part.

13. The light-emitting device according to claim 12, wherein the support part is located further in the one direction than the midpoint between the end of the first light-emitting unit in the one direction and the end of the second light-emitting unit in the one direction.

14. The light-emitting device according to claim 13, wherein the support part is located further in the one direction than the end of the second light-emitting unit in the one direction.

15. The light-emitting device according to claim 12, further comprising:

a base located in a direction opposite to a light-emitting direction, in which the first light-emitting unit emits light, with respect to the first light-emitting unit, the base having the first light-emitting unit and the second light-emitting unit placed thereon,

wherein the support part is provided on the base.

16. The light-emitting device according to claim 15, further comprising:

a removably attachable member that is removably attached to the base at a side of the base in a width direction,

22

wherein the width direction is a direction that crosses the light-emitting direction and the one direction, and wherein the support part is not fixed to the removably attachable member.

5. The light-emitting device according to claim 15, wherein at least a portion of the support part is provided on the base at a position such that the portion overlaps at least one of the first light-emitting unit and the second light-emitting unit when viewed in the one direction.

18. The light-emitting device according to claim 15, wherein each of the first light-emitting unit and the second light-emitting unit includes:

a light-emitting member that emits light in the light-emitting direction; and
a body that supports the light-emitting member at a side of the light-emitting member in the direction opposite to the light-emitting direction, the body being constituted by a metal block, and

wherein the base is a metal block to which the body is attached at a side of the body in the direction opposite to the light-emitting direction.

19. The light-emitting device according to claim 12, wherein the cleaning unit is a first cleaning unit, wherein the transmission part is a first transmission part, wherein the extending part is a first extending part, wherein the light-emitting device further comprises:

a second cleaning unit that is configured to move in the one direction and the opposite direction to clean the second emission surface;
a second transmission part that is disposed at a position shifted from the first transmission part in a width direction, that extends from the second cleaning unit in the one direction, and that transmits a moving force for moving the second cleaning unit to the second cleaning unit; and

a second extending part that extends from the second transmission part in the one direction to elongate the second transmission part,

wherein the width direction is a direction that crosses a light-emitting direction, in which the first light-emitting unit emits light, and the one direction, and wherein the support part supports the first extending part and the second extending part.

20. The light-emitting device according to claim 12, wherein the cleaning unit is a first cleaning unit,

wherein the light-emitting device further comprises:
a second cleaning unit that is configured to move in the one direction and the opposite direction to clean the second emission surface,
wherein the first light-emitting unit and the second light-emitting unit are aligned along the one direction,
wherein the second cleaning unit is attached to the extending part, and
wherein the support part is disposed between the first light-emitting unit and the second light-emitting unit.
